UNITED STATES PATENT OFFICE.

WILLIAM HOLT, OF CHICAGO, ILLINOIS; MARY A. HOLT, EXECUTRIX OF SAID WILLIAM HOLT, DECEASED, ASSIGNEE TO THE PEERLESS MOISTENER CO., A CORPORATION OF ILLINOIS.

MOISTENER.

1,245,342.

Specification of Letters Patent.

Patented Nov. 6, 1917.

Application filed September 21, 1916. Serial No. 121,349.

To all whom it may concern:

Be it known that I, WILLIAM HOLT, a citizen of the United States, residing in Chicago, in the county of Cook and State of Illinois, have invented a new and useful Improvement in Moisteners, of which the following is a specification.

This invention relates in general to moisteners and has more particular reference to moisteners provided to moisten the hands of persons bowling in a bowling alley.

It will be manifest, however, that certain features of the invention have other and more general application.

Prior to my invention it has usually been the custom in bowling alleys to provide a dampened sponge resting in a cup fastened upon the post at the end of the ball return. This arrangement has been unsatisfactory for many reasons, for example, it is unsanitary and the sponge soon becomes very much discolored from the dirt taken from the hands of the users. Furthermore the sponge is frequently removed and mislaid or lost. Also the sponge supplied frequently too great a quantity of water.

It is a principal object of my present invention to provide a moistener for the hands which will be sanitary and which will always be available for the use of the player.

A further object of the invention is the improved construction of moisteners for this and other purposes, as for example, moistening the flaps of envelopes, stamps and the like, certain features of this invention having a desirable application in said structures.

A still further object of the invention is the provision of a moistener of such character which can be readily cleaned and which at the same time will not likely be tampered with by the users of the bowling alley.

An additional object of the invention is the provision of a moistener of simple durable and economical construction.

Other objects and advantages of the invention will be apparent as it is better understood from the following description when considered in connection with the accompanying drawing illustrating a preferred embodiment thereof.

In the drawing forming a part of this specification,

Figure 1 is a partial elevation of a part of a bowling alley;

Fig. 2 is a top plan view with parts broken

away of a moistener embodying my present invention;

Fig. 3 is a section taken diametrically of the moistener.

Fig. 4 is an isolated side elevation of the cover; and

Fig. 5 is an isolated perspective view of the felt support.

For the purpose of illustrating my invention I have shown on the drawing a part 65 of a bowling alley, the delivery end 6 of the ball return 7 being shown as fastened in the usual manner and supported from the post 8. The post 8 is provided with a flat top 9 in which is formed a recess 11 for the reception of the moistener. This moistener consists of a water vessel A, a cover B therefore, a piece of felt C for supplying moisture through the perforations of the cover and a support D for the felt. The water vessel A 75 in the present instance consists of a body part 12 having a depression 13 extending annularly about its center and in its bottom. The top of the body is necked outwardly at 14 for the reception of the cover 80 and the body is provided with a peripheral flange 15 adapted to rest upon the top of the post. Three pins 16 are provided upon the inside of the necked portion 14 to extend inwardly, these pins being for the purpose of 85 engaging slots, to be presently described, in the cover to lock the cover in place.

The support D in the present instance consists of a cylinder 17 closed at its top at 18 and having openings or perforations 19 90 on opposite sides. The lower edge of the cylinder rests in the depression 13 and its top is disposed just beneath the normal position of the cover. The piece of felt C consists of a center circular body 21 and two diametrically extending flaps 22 each of which flaps is adapted to be inserted into an opening or aperture 13 of the support. As will be noted on the drawing this felt is relatively thick and its tendency to straighten 100 out holds the flaps firmly in the supports so that the two may be removed as a single unit. The cover consists in the present instance of a perforated top 23 and a side flange 24 adapted for insertion in the neck 105 14 of the body. Slots corresponding in number to the number of pins 16 are provided and each of these slots is formed by merely pressing in the flange material. The slots have an opening 25 at either edge and 110

are inclined upwardly at 26 toward the position of the pins when in locking position. At the locking position of the pins the slots extend downwardly at 27 so that the pins drop behind shoulders 28. This construction gives the cover a slight vertical movement while in the interlocking position. The parts are so dimensioned that the felt normally holds the cover elevated with the pins in the parts 27 of the slots. To remove the cover it is therefore necessary to press down upon it, give it a slight turning movement to cause the pins to pass through the slots and then lift it up away from the vessel. This movement is not one that will occur to persons idly toying with the moistener when in place upon the post of a bowling alley or when positioned in other localities and yet it permits the cover being removed by anyone who knows the construction or anyone making conscious effort to remove it.

The form of support used is believed to be of considerable value as it effectively supports the felt and causes it to be held in substantial contact with the cover, the yielding action of the cover being in this instance controlled by the compression of the felt.

Since the support and felt can be removed as a single unit it is relatively easy to clean the device, it only being necessary to hold the felt and support under a running water faucet and to wipe out the inside of the vessel as occasion may require. Furthermore in placing the flaps 22 through the perforations or openings 19 the body of the felt is caused to bend upwardly at its center and its natural cushioning effect thereby increased.

It is thought that the invention and many of its attendant advantages will be understood from the foregoing description, and it will be apparent that various changes may be made in the form, construction and arrangement of the parts without departing from the spirit and scope of the invention or sacrificing any of its material advantages,

Copies of this patent may be obtained for five cents each, by addressing the "Commissioner of Patents, Washington, D. C."

the form hereinbefore described being merely a preferred embodiment thereof.

I claim:

1. A moistener comprising a water vessel; a perforated cover therefor; a piece of felt adapted to supply moisture through the perforations of said cover; a cylinder resting upon the bottom of said vessel and disposed beneath said felt; said cylinder having means at its top for holding the felt in proper position beneath said perforated cover.

2. A moistener comprising a water vessel; a perforated cover for said vessel; a piece of felt adapted to supply moisture through the perforations of said cover and a support for said felt for holding it in proper relation with respect to said cover; said support and felt being connected to permit removal of the support and felt as a single unit.

3. A moistener comprising a water vessel; a perforated cover therefor; a piece of felt for supplying moisture through the perforations of said cover; a support for said felt, said support comprising a cylinder having perforations in its side through which depending parts of the felt extend, said cylinder having a horizontally extending support at its top between the depending parts of said felt.

4. A moistener comprising a water vessel; a perforated cover therefor, said cover and vessel having a pin and slot connection the slots of said connection being inclined toward locked position and having a downwardly extending part at locked position; a piece of felt for supplying moisture through the perforations of said cover, and means locking said felt against said cover when said pins are resting in the lower parts of said slots in locked position.

Signed in the presence of two subscribing witnesses.

WILLIAM HOLT.
